Primary Examiner — April Rivas(74) *Attorney, Agent, or Firm* — Wolf, Greenfield & Sacks, P.C.(57) **CLAIM**

The ornamental design for a luggage, substantially as shown and described.

DESCRIPTION

FIG. 1 shows a top, front, right side perspective view of the design.

FIG. 2 shows a front view of the design.

FIG. 3 shows a rear view of the design.

FIG. 4 shows a right side view of the design.

FIG. 5 shows a left side view of the design.

FIG. 6 shows a top view of the design; and,

FIG. 7 shows a bottom view of the design.

Any broken lines shown in the drawings represent unclaimed portions of the luggage and form no part of the claimed design.
